UNITED STATES PATENT OFFICE.

JOHN S. HOOPER, OF WILKINSBURG, PENNSYLVANIA.

BATTERY FILLER.

Application filed December 8, 1925. Serial No. 74,126.

This invention relates to certain new and useful improvements in battery filling devices, and has more particular reference to a device for containing water and dispensing the same so as to fill the cells of a storage battery with facility.

The invention contemplates the provision of a jar provided near the bottom of the same with an outlet with which is associated an outlet hose and nozzle, and a simple and durable form of carrier in which the jar is removably positionable.

The primary object of the invention is to provide a battery filler of the above kind which is extremely simple and durable in construction.

A further object is to provide a device of the above kind wherein the jar carrier embodies means for releasably holding the nozzle carrying hose adjacent the jar in an elevated position when not in use.

Other objects will appear as the nature of the invention is better understood, and the same consists in the novel form, combination and arrangement of parts herein-after more fully described, shown in the accompanying drawings and claimed.

In the drawings, wherein like reference characters indicate corresponding parts throughout the several views,

Figure 1 is an elevational view of a battery filler constructed in accordance with the present invention;

Figure 2 is a top plan view thereof;

Figure 3 is a horizontal section taken substantially upon line 3—3 of Figure 1; and

Figure 4 is an enlarged fragmentary section disclosing the manner of providing the jar with an outlet.

Referring more in detail to the drawings, the present invention embodies a jar carrier consisting in an inverted pan-shaped base 5 preferably formed of sheet metal and having a horizontal continuous flange 6 at its lower edge adapted to rest flatly upon a supporting surface when the device is not in use. The jar carrier further embodies a plurality of upright strips 7 and 8 whose lower ends are directed inwardly and terminate in L-shaped feet 9 which are secured to the top of the base member 5 by riveting or the like as at 10. The strips 7 and 8 are preferably disposed in uniformly spaced relation, and the strips 7 preferably consist in a pair diametrically disposed

between the pair of strips 8 and shorter than the latter. The strips are rigidly connected by means of a hoop 11 disposed horizontally and riveted or otherwise secured as at 12 to the strips. This hoop 11 is attached to the upper ends of the shorter strips 7 but secured to the longer strips 8 at a point below the upper ends thereof, and portions of the strips 8 thus project above the hoop 11 and are provided in their upper free ends with transversely aligned openings in which are journaled the outturned ends of a bail or handle 13, by means of which the device may be conveniently carried about.

The device further embodies a jar 14 of a size to fit somewhat snugly within the carrier and to project above the hoop 11, and this jar has the usual neck on which is placed the usual removable cover 15. The jar 14 is thus adapted to rest upon the in-turned ends of the strips 7 and 8 with its central portion held in spaced relation to the base 5 by means of the feet 9 of said strips. The jar 14 has an outlet in the side thereof adjacent the bottom wall of the same, and this outlet is preferably constructed as shown in Figure 4. As illustrated, the jar is formed with an opening 16 through which is inserted a tube 17 having a head 18 formed on its inner end. The intermediate portion of the tube 17 is threaded for reception of a nut 19, and disposed on the tube at each side of the jar wall between the head 18 and nut 19 are suitable gaskets 20. It is thus evident that when the nut 19 is tightened the same is forced toward the jar and the tube 17 is drawn outwardly so that the gaskets 20 are tightly compressed against opposite sides of the jar wall for sealing the joint between the tube 17 and the jar wall whereby the liquid may not leak through the opening 16. A flexible tube or hose 21 is forced onto the projecting outer end of the tube 17 and has a stiff tube or nozzle 22 inserted in the other end thereof so that the liquid dispensed from the jar may be properly directed into the battery cells.

Suitably attached to the upper portion of one of the strips 8 is a sheet metal clasp 23 adapted to releasably engage the outlet tube or hose 21 for maintaining the same in an elevated position adjacent the jar when the device is not in use. The upper end of the other strip 8 carries a larger sheet metal

clasp 24 for releasable retaining reception of a hydrometer so that the latter may be within convenient reach for testing the battery as its cells are filled with water.

It is obvious that the jar 14 is filled by removing the cover 15, and as the water in the jar will become mixed with acid from the battery cells, the tube 17 and adjacent parts within the jar are preferably formed 10 of lead so that the acid will not have a destructive effect thereon.

The cover 15 of the jar is provided with a suitable vent opening as indicated by dotted lines in Figure 2 at 25 so that the water 15 may readily flow from the jar through the outlet tube 21. In using a device of this character it is simply necessary to allow the outlet tube 21 to depend from the bottom of the jar and to hold the latter at an elevation 20 above the battery, whereupon the water will flow from the jar by gravity into the cells of the battery. By raising the outlet tube 21 and engaging the same with the clasp 23 as shown in Figure 1, the flow of water will 25 be immediately cut off.

Minor changes may be made without de-

parting from the spirit and scope of the invention as claimed.

What I claim as new is:—

1. In a battery filler of the character described, an open jar carrier embodying a base, a body connected with the base, the body having a lateral offset portion adjacent its lower end and disposed above said base for supporting reception of a jar whereby the jar will be held above said base. 30

2. In a battery filler of the character described, a jar carrier embodying an inverted pan-shaped base, a plurality of equally spaced upright strips attached at their lower ends to said base, a hoop rigidly connecting the upper end portions of the strips, certain of said strips projecting upwardly past the hoop in opposed relation, and a bail hinged to the upper ends of the 40 said certain strips, said strips having inwardly directed lower ends adapted for supporting reception of a jar and terminating in angular feet attached to the base. 45

In testimony whereof I affix my signature.

JOHN S. HOOPER.
